(57) **CLAIM**

The ornamental design for a combined speaker with lamp, as shown and described.

DESCRIPTION

FIG. 1 is a front, top perspective view of a combined speaker with lamp, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1;

FIG. 10 is an enlarged view of detail "10" identified in FIG. 1; and,

FIG. 11 is an enlarged view of detail "11" identified in FIG. 2.

The dashed broken lines in the figures illustrate portions of the combined speaker with lamp that form no part of the claimed design. The dash dot dash broken lines in FIGS. 1, 2, 9, 10 and 11 are for the purpose of illustrating the enlarged view indicators and form no part of the claimed design.
